T. Bruff,

Shot Machine,

Patented June 4, 1813.

Thomas Buff

Seller of Patent

The Schedule referred to in these Letters Patent and making part of this document containing a description in the words of the said Thomas as Buff himself of his machine for making shot or by process

This machine for making pointed shot from flat bars of lead consists of two stitting and one pressing roller with its curve all of steel, case hardened iron, or hard brass, in a frame of metal. The stitting rollers are placed horizontally at the top, are grooved lengthwise with almost half circular grooves, a little widened at the top, to let the lead pass freely from them to the pressing part beneath. The grooves in each roller are exactly alike and facing each other all round so as to let the bars crop out almost as round as wire. Between the grooves a plain space is left about the width of a small pea head where the lead between the wires is compressed to the size of thin paper for the purpose of holding the pieces together till it conducts them to the mouth of the pressing roller and curve. The pressing roller should be about a third larger than the stitting rollers, and placed with the top or mouth of the curve immediately under the dividing line between them, to receive the stitted bar as it comes from them. This roller is grooved round its circumference in perfect half circular grooves, so near each other as to bring their metal almost to an edge between, and as many in number as will comprise the width of the bar making them about a width wider than the groove of the stitting rollers, to allow for the increase of diameter of the shot as they are formed. On one side of the pressing roller is the curve grooved like the roller with the grooves facing each other. it is, fixed to the frame and follows the curve of the roller except a gradual widening from near the middle to the top, leaving a space between at top sufficient to receive one piece at a time of the broken wire or stitted bar as they

come from the slitting rollers. The length of the curve must be in proportion to the size of the shot to be made by it, which to make them perfectly round must be rolled over twice between the rollers and curve after it leaves the diverging and dividing part at the top, and the curve should be gradually turned in till it reaches the bottom, to give the shot an easy delivery from the grooves.

The slitting rollers have small coggs on one end to make them keep pace with each other, and on the other end of one of them and on one end of the pressing roller are two other coggs of equal size, and when force is applied to the handle of the pressing roller they all move together, and the pressing roller moves one third faster than the slitting rollers in consequence of its greater diameter, gives room for the pieces to move clear of each other. When the slitting is performed by the upper roller, and the bar suspends from them by the thin plate between the slitted pieces to the mouth of the pressing part, the motion of the pressing roller draws them into the mouth of the curve, takes them off one by one, divides and rounds them into perfect shot and rolls them out at the bottom of the machine. The casting apparatus consists of iron ingots and caldron set over a furnace for melting lead, and heating heating the ingots at the same time. The number of ingots will depend on the number of bars to be cast at a time, they should be from two to two and a half feet in length, may be made of any width with divisions the exact breadth of the bars intended to be cast, the breadth of the bars must correspond with the length of the grooves in the slitting rollers and their thickness, the diameter of the shot intended to be made from them.

The ingots are made in two flat plates, one of them plain, or a moulding at the top and flat at bottom to keep the metal in one at a proper distance from it, the other like it, except a projection on the inside of the sides and bottom, the thickness of the bars and about half an inch from the edges to admit of forming

ruled in between them with the fingers to keep them perfectly tight.
 The moulding on the top and round on the bottom, outside of the
 ingots must be about half an inch deep to keep them far enough
 apart to admit the heat from the fire of the furnace to pass free-
 ly between them that they may be heated to the tops. The tops must be
 squared and leveled to form an even surface when all in their places.
 They are set perpendicular on one or both sides of the caldron,
 their bottoms resting on arches of cast iron in rows, pointing toward
 the caldron with their feet on flat cast iron plates, placed horizon-
 tally with the bottom of the furnace. The upper edges of the so arches
 straight that the ingots may stand perfectly level on them, the ingots
 are enclosed in a light iron frame at top, and the wall of the furnace
 on the outside and ends. If the dipping ladle and stoker are
 used, the tops of the caldron may be almost level with the tops of
 the ingots and the bars when drawn may be trimmed to the p[er]
 in a gauge box, with a cutter like a draw knife working on [a]p[er]t[ure]
 When drawn are necessary for nice work they may be of cast iron
 or brass, and large enough to cover all the ingots on one side
 of the caldron or in convenient divisions, each draw consists of
 a flat plate to rest on the tops of the ingots having holes pierced
 in them corresponding in size and form with the open tops
 of the ingots and directly over them. They must have a high edg-
 ing around them to keep on the superfluous lead, the lead to be
 discharged from a spout or cock over each draw, and when the ingots
 are charged, the draw must be moved forward a little more than the
 breadth of the holes and left to cool. To use this machine it
 is only necessary when a moderate force is applied to pull the end
 of a bar made as above discolored, into the mouth of the conduct
 or at top, and you have nothing to do but to receive the shot into
 a bag or box at bottom. By adding a wooden frame with a
 sloping bottom toward the conducting groove. You may place
 almost any number of bars retaining against the grid, and

they will succeed with their improving the manufacture and will
work with shot in succession. To give the shot a high
rise, the method used in the shot factory is sufficient,
turn them gently in a large iron cylinder, about two
ales with a little powder of black lead.
